FIRE EXTINGUISHING SYSTEM

Harry C. Grant, Jr., New York, N. Y., assignor to
 Specialties Development Corporation, Bloom-
 field, N. J., a corporation of New Jersey

Application February 25, 1941, Serial No. 380,429

11 Claims. (Cl. 169—11)

The present invention relates to a fire extinguishing system, and more particularly to automatic control devices for such a system for discharging a fluid medium under pressure.

The present invention is particularly adapted to be utilized in connection with a fire extinguishing system which comprises a source of a fire extinguishing fluid under pressure, a plurality of discharge conduits for conducting the fluid to one or more of several locations where a fire may occur, branching off from a main fluid conducting conduit, and a valve in each branch conduit adapted to be opened in the event of fire. The valves employed usually are of the fluid pressure operated type, and may be provided with manually, mechanically or electrically operable means for selectively controlling the operation thereof.

In systems of this type, after a fire has been extinguished by the flow of fluid from one of the selected discharge conduits, the valve in the branch conduit will usually tend to reseat itself, as for instance by spring action. However, a frequent difficulty is that the means for controlling the opening of the valve by pressure do not return to their initial, unoperated positions, so that in the case of another fire, regardless of its location with respect to the system, the same branch valve is again opened and fluid is discharged. This is objectionable because, if the fire is at another location, fluid will be discharged from at least two conduits. Half of the fluid will be wasted, and may cause personal injury and property damage. Furthermore, due to this waste, the amount of fluid supplied to the fire may be insufficient to extinguish it rapidly and thereby prevent the fire from spreading or getting out of control.

The present invention aims to eliminate the foregoing difficulties by providing in a system of the type described, suitable control devices, which insure the operation of the valve intended to be operated; and providing indicating devices, which enable the operator to determine, whether or not the valve and its control devices have been properly operated.

An object of the present invention is to provide a system of the foregoing character comprising branch conduit distribution valves which are held open until the fire extinguishing medium is completely discharged and are returned to their initial position after each operation, whereby they will be ready for operation when the next emergency occurs.

Another object of the invention is to provide

distribution valves in systems of the foregoing character, having self-resetting control means.

Another object is to provide means for indicating the operation of the valve and its control means whereby operation thereof can be observed at a remote location.

A further object is to provide indicating and control means for accomplishing the foregoing objects, which are simple and inexpensive; effective in operation; requires a minimum of maintenance and repair; and can be readily embodied in existing or newly installed systems.

Other and further objects will be apparent as the invention is described in greater detail in connection with the accompanying drawings wherein:

Figure 1 is a diagrammatic view of a fire extinguishing system and a wiring system therefor, illustrating an embodiment of the invention;

Figure 2 is an enlarged sectional view of a valve, illustrating the valve closed and the control means therefor in unoperated position prior to the occurrence of a fire;

Figure 3 is a fragmentary sectional view, illustrating the valve control means of Figure 2 in actuated position prior to the opening of the valve itself;

Figure 4 is a fragmentary sectional view, illustrating the valve control means in operated position after the valve itself is opened; and

Figure 5 is a fragmentary sectional view, illustrating modified means for actuating the valve opening control devices.

In Figure 1 there is shown a fire extinguishing system in which the present invention may be utilized. The system may comprise a centrally located container 10 for storing a fluid fire extinguishing medium, such as carbon dioxide under pressure, and a main discharge conduit 11 connected to the container and provided with a main control valve 12. Along the main conduit 11, a series of branch or distributing conduits 14 is provided, and these branch conduits 14 may extend to various locations throughout a building, ship, aircraft or other structure where the system may be utilized. While three of such branch conduits 14 are illustrated, it will be understood that any suitable number may be employed depending on the size and the design of the structure in which the system is installed.

In each of the branch conduits 14, a branch control valve 15 is provided, which may be electrically, mechanically, pneumatically, or manually actuated. For purposes of illustration, the valves 15 may each be operated through the

medium of a pilot valve 16, which in turn may be actuated electro-magnetically (Figures 2, 3 and 4) or mechanically (Figure 5). As shown more particularly in Figure 1, the pilot valves 16 are each adapted to be selectively and independently actuated electro-magnetically from a switch or control panel 17 by a series of normally open switches 19, respectively connected by an electrical circuit to the electro-magnetic devices of the pilot valves. Such a circuit may comprise a lead 20 extending from one terminal of the switch to one terminal of the electro-magnetic device, a lead 21 extending from the other terminal of the electro-magnetic device to one terminal of a source of electrical energy, such as a battery 22, and a lead 24 extending from the other terminal of the battery to the other terminal of the switch 19.

As mentioned previously herein, the present invention, among other objects, contemplates providing each of the branch valves 15 with a device for indicating when the valve control devices (which will be described in detail hereafter) are not reset. Such an indicating device may comprise a normally open switch 25 operatively associated with the valve 15, and electrically connected to a lamp 26 or the like on the control panel 17. The electrical connections comprise a lead 27 extending from one terminal of the lamp 26 to one terminal of the switch 25, a lead 29 extending from the other terminal of the switch to one terminal of the battery 22 by way of the lead 21, and a lead 30 extending from the other terminal of the lamp 26 to the other terminal of the battery 22 by way of the lead 24.

Referring more particularly to Figure 2, there is shown in detail one unit, comprising one of the branch conduit control valves 15, its pilot valve 16, and the operating and indicating devices associated therewith. Since all these units are similar in design, a description of one will suffice for all.

The valve 15 may be of the self-seating type, and has an inlet 35, an outlet 38, and a valve seat 37 intermediate the inlet and outlet adapted to receive a valve member 39 which is normally held in valve closing position by one end of a spring 40, the other end of which is seated in an annular groove 41 in the interior wall of the valve housing. In order to unseat the valve member 39 and open the valve, a cylinder 42 is provided on the exterior of the valve housing, and a piston 44 is positioned therein, connected to the valve member 39 by a piston rod 45, extending from the cylinder 42 to the interior of the valve through an aperture 46. The cylinder 42 and piston 44 have a greater area than the area of the valve member 39 upon which pressure is effective. The resistance of the spring 40, when suitably tensioned, can be overcome by introducing pressure from the inlet side 35 of the valve into the cylinder 42 to cause the piston 44 to move upwardly, whereby the connecting piston rod 45 unseats the valve member 39 to open the valve. Pressure may be introduced into the cylinder 42 through a conduit or passage 47 in the valve housing, the pilot valve 16, and a second passage 49 leading from the pilot valve to the cylinder. If desired, the upper end of the piston rod may be provided with a stem portion 50, adapted to protrude through an aperture in a cylinder cover (not shown) to indicate when the valve member 39 is unseated and the valve is open. While pressure operated means for opening the valve are shown herein, it will be under-

stood that manually operated or other suitable means with or without the intermediary of a pilot valve may be utilized for opening the valve.

The pilot valve, preferably, is arranged intermediate the passages 47 and 49 by providing a bore in the valve body, which is suitably threaded for receiving a casing 55 of the pilot valve. The lower portion of the casing 55 has an inner bore 56, providing a cylinder for a pilot valve member 57 adapted to be normally urged against a valve seat 59 by a spring 60 under compression. Adjacent the valve seat 59 is a valve opening 61, which is in communication with passages 62, adapted to admit pressure passing through the pilot valve to the passage 49.

In order to attach devices for moving the pilot valve member 57 away from the valve seat 59, the upper end of the casing 55 is provided with a bore 64 for receiving the lower end 65 of a housing 66 of the pilot valve opening device. The housing 66 has an outwardly extending flange 67 adapted to overlie the upper edge of the valve casing 55, and is held in place by a cap member 69 threaded to the upper end of the casing 55. The cap may have an inwardly extending flange 70 engaging the flange 67.

The housing 66 has a bore 71 adjacent its lower end for receiving a piston or plunger member 72 which may be in the form of solenoid core. This piston member 72 is provided with a downwardly depending stem or rod portion 74 adapted to extend through an aperture 75 in the bottom of the housing 66 and into the valve opening 61, whereby upon downward movement of the member 72 the stem portion 74 engages and unseats the pilot valve member 57. Normally, the stem or rod portion 74 is held out of engagement with the pilot valve member 57 by a spring 76 engaging the under side of the piston member 72. Upward movement of the piston member 72 may be limited by a stop 73 at the upper end of the housing 66. This stop may be provided with a screw 78 for adjusting the extent of upward movement of the member 72.

In the event, it is desired to move the piston member 72 into pilot valve operating position by electro-magnetic means, a solenoid winding 77 is disposed about the housing 66 which, in this instance, will be constructed of non-magnetizable material, as will other elements closely associated with the winding and the core. The winding 77 may be secured to the housing 66 by upper and lower disks 79 and 80. The solenoid winding 77 has a pair of terminals to which are connected the leads 20 and 21 of the electrical circuit described in connection with Figure 1.

To accomplish one of the principal objects of the invention, namely, to cause an actuation of the valve control means for a sufficient duration to assure a fully effective discharge of the fluid under control of the valve, and, subsequently, to cause the valve and its control means to return to its initial position, suitable devices are associated with the piston member 44, which are operative in response to movements of the plunger member 72, and are also adapted to actuate the indicating means referred to in connection with Figure 1.

Such devices may comprise a latch member 85, pivotally mounted at 86 on an extension member or arm 87 on the housing 66. The latch member has a finger 89 at one end, which is positioned to engage the outer side wall of the plunger member 72, when said plunger is in its upper position. When the plunger member 72 is in

its lower position, the finger 89 is adapted to extend over, and engage, a shoulder 90 at the upper end of the piston member 72, locking the piston member and the pilot valve member 57 in the lower or operated position, as shown in Figure 3. At its other end the latch member has an arm 91, which is positioned to engage and move the switch 25 into circuit closing position. To effect pivotal movement of the latch member 85, the arm 91 has one end of a spring 92 attached to it at 94, while the other end of spring 92 may be secured to an ear 95 of the extension 87. The spring 92 is tensioned, so that upon downward movement of the piston member 72, the finger 89 swings downwardly over the shoulder 90 to lock piston member 72 in its actuated position, as shown in Figure 3 and the arm 91 closes the switch 25.

It is intended to permit the pilot valve 16 to close only after the valve 15 has been fully opened and a complete discharge of the fire extinguishing medium has taken place. Means are therefore provided for resetting the latch member 85 after such discharge has taken place. Such means may comprise an upright rod 96, secured into piston 44 and movable therewith, and an actuating lever member 100, pivoted at 101 on the end of the rod 96, which tends to rotate counterclockwise by the action of a spring 102. One end 103 of the spring is secured to rod 96, and its other end 104 is secured to an ear 105 of lever 100. A stop pin 106 on rod 96 maintains the lever 100 in upright position as shown. The rod 96 and the lever 100 are positioned, so that a latch formation 107 on the lever 100, upon upward movement of the piston 44, rides past an offset 108 on the arm 91 of the latch member 85, the lever 100 being rotated in a clockwise direction in opposition to the spring 102. A shoulder 109 of the latch member 100 then latches into place over the offset 108, as shown in Figure 4.

When a fire occurs, the main control valve 12, and the distribution valve 15, controlling the branch conduit for the fire extinguishing medium at the location of the fire, are opened either manually or automatically, in the latter case, by a momentary closing of the switch 19 of the respective valve 15. Closing of the switch 19 causes the solenoid 77 to be energized, whereby the solenoid piston or plunger 72 is moved downwardly, and its stem or rod portion 74 engages and unseats the pilot valve member 57. This enables pressure in the branch conduit 14 to pass through the passage 47, past the pilot valve member 57, through the passage 49, and into the cylinder 42, to cause the piston 44 therein to be moved upwardly, whereby the valve member 39 is unseated, and the valve 15 is opened to release the fire extinguishing medium.

As illustrated more particularly in Figure 3, the solenoid piston 72 is shown moved downwardly, and the latch finger 89 as being urged by the spring 92 to extend inwardly and over the shoulder 90 of the piston 72. This arrangement acts as an electromechanical relay, in that energization of solenoid 77 for even the briefest duration, results in the actuation of the latch member 85, whereby the pilot valve member 57 is held in an open position. This insures that valve member 39 may be operated and kept open as long as pressure is effective at the inlet 35.

As the finger 89 of the latch member is moved into locking position, the arm 91 at the other end of the latch member engages the switch 25 to

close the indicating lamp circuit, whereupon the lamp 26 on the panel 17 is illuminated and the operator knows that the pilot valve is open to admit pressure medium to the valve opening cylinder 42. When such pressure medium is admitted, the piston 44 in the cylinder 42 and the rod 96 thereon are moved upwardly. When approaching the uppermost position, the latch formation 107 of the lever 100 on the rod 96 frictionally engages the offset 108. Further upward movement of the rod 96 results in the latch 107 snapping into place over the offset 108 (Figure 4). By providing this offset the upward movement of the lever 100 does not affect the indicating circuit switch 25, which, as was shown above, is actuated by arm 91. The fire extinguishing medium is now able to discharge through the open valve. Although the indicating lamp 26, in the embodiment shown, is employed as indicating means for the pilot valve, it will be understood that in the absence of such a pilot valve, the operation of the main valve member 39 itself may be indicated similarly.

After the fire has been extinguished, the main valve 12 is closed, and conduits 11 and 14 are restored to atmospheric pressure. The pressure medium trapped under the valve opening piston 44 is gradually forced out through passages 49 and 47 by the action of the valve spring 40, which urges the valve member 39 against the seat 37 toward its closed position.

The downward movement of the piston 44 and the rod 96 causes the latch formation 107 to depress the arm 91, and to rotate the latch member 85 in a clockwise direction, until the extreme end of the finger 89 is moved out of the path of movement of the piston or plunger 72. Once the finger is clear of the piston 72, the spring 76 forces the piston upwardly, and returns it to the position shown in Figure 2. At the same time, the spring 60 reseats the pilot valve member 57. If, at any time after the fire, or after the main valve 12 is closed, the lamp 26 remains illuminated, a warning is conveyed to the operator that the particular branch valve 15 will open upon admission of pressure medium to the conduit 14. The pilot valve is then unlatched to permit it to reclose, and to insure that it is not in valve opening position, at the time of a subsequent fire. The danger of fire extinguishing medium being discharged at an undesired location is thus eliminated.

In Figure 5, a modified embodiment of the invention is illustrated, which differs essentially from the embodiment shown in Figures 2, 3 and 4, in that the pilot valve is here actuated by a pull cord instead of a solenoid device. A housing 66' encloses a piston or plunger 72', and is formed with a slot 81, at its upper end. The housing also has a screw 78', threaded through the top, which acts as an adjustable element of a stop 73' for the piston 72'. The housing may also have an outwardly extending ear or lug 82 for pivotally mounting a bell crank 83. One end of the bell crank 83 extends into a slot formed in the piston 72', and is pivotally connected thereto by a pin 84. A pull cord 23 is attached to the other end of the bell crank, and the cord may extend through suitable tubing (not shown) to a central control station.

A latch member 85 is provided, which may be mounted on an extension ear or lug 87' of the housing 66', and is adapted to operate like the latch member described in connection with Figure 2. The latch member is urged into a plunger

locking position by a spring 82, which may be secured similarly to the corresponding member in the construction of Figure 2. The reset rod may also be of a design similar to that described in the previous drawings. Any other suitable means for attaching the spring and mounting the reset rod may be utilized.

The operation of the modified embodiment shown in Figure 5 need not be described in detail, since it operates similarly to the device illustrated in Figures 2, 3 and 4. The essential difference is, that the pilot valve operating piston 72' is moved downwardly, in response to a pull on the cord 23, instead of electromagnetically. By pulling the cord, the bell crank 83 swings about its pivot, and the end attached to the piston 72' imparts downward movement to the piston 72'. Subsequent valve operation, and functioning of the indicating and latching means, is effected as described in connection with the preceding illustrations.

From the foregoing description, it will be seen, that the present invention provides an improved fire extinguishing system. It will be observed, that the devices for actuating or controlling the operation of the valve opening piston are retained in effective position by latching means until the valve has begun to return toward its closed position. In this manner, proper opening of the valve and a full discharge of the fire extinguishing medium is insured. After the discharge of the fluid medium has been effected, the latching means are rendered ineffective, whereby the actuating or controlling devices are permitted to return to their initial and non-actuated position, to insure proper operation of the valve when it is so desired. At the same time, the indicating means cooperate with the valve controlling devices, and enable the position of the valve controlling devices to be determined from a remote location.

It will be appreciated that the principle of operation of the foregoing described system, which comprises moving the valve control means and maintaining the control means in a position to permit operation of the valve opening means in response to the pressure medium, releasing the pressure medium to operate the valve opening means, maintaining the control means in a position to permit continued operation of the opening means, and returning the control means to their initial position upon closing of the valve, may be utilized in embodiments other than shown herein for illustrative purposes. For example, the foregoing operations may be accomplished by a valve provided with mechanical means which eliminate the necessity of a pressure admitting pilot valve.

It is, therefore, to be understood, that, although I have shown and described a specific embodiment of my invention, I am fully aware that many modifications thereof are possible, and that the present invention, while it has been described with specific reference to the accompanying drawings, is not to be limited save as defined in the appended claims.

I claim:

1. In a fire extinguishing system, a fire extinguishing medium control valve of the type having an inlet and an outlet separated by a valve seat, a valve member, means for normally urging said valve member against said valve seat, a cylinder provided with a bore of greater area than said valve member and with an aperture adjacent said valve member, a piston in said cylinder, a piston rod extending through the aperture and connecting said valve member and piston, said valve

having a passage for introducing pressure from the inlet side of the valve to said cylinder; in combination with a pilot valve positioned in said passage and having a valve chamber and a valve seat, a valve member in said pilot valve chamber, and means for normally urging said pilot valve member against said pilot valve seat; a movable member adapted to engage and unseat said pilot valve member, means for normally urging said movable member away from said pilot valve member; remotely controllable means for moving said movable member to unseat said pilot valve member; indicating means, including an element operable in response to movement of said movable member and adapted to retain said movable member in position to unseat said pilot valve member, said indicating means being adapted to indicate that said pilot valve member is unseated; and a member adapted to engage and move said element of said indicating means into a position to release said movable member, said last member being positioned to be moved by said piston in said valve cylinder.

2. In a valve device, the combination of a main valve member, a valve seat, means for normally urging said valve member against said valve seat, means for moving said valve member away from its seat, means for initiating operation of said valve member moving means, means for normally maintaining said last means in an ineffective position; a movable member adapted to engage and move said initiating means into effective position, means for normally urging said movable member out of engagement with said initiating means; remotely controllable means for moving said movable member; an element operable in response to movement of said movable member and adapted to retain said movable member in position to engage and maintain said initiating means in effective position; and a member movable with said valve member moving means adapted to engage and move said element into a position to release said movable member.

3. In a valve device, the combination of a main valve member, a valve seat, means for normally urging said valve member against said valve seat, pressure operated means for moving said valve member away from said valve seat; a pilot valve for admitting a pressure medium to said pressure operated means having a valve chamber and a valve seat, a valve member in said pilot valve chamber, and means for normally urging said pilot valve member against said pilot valve seat; a movable member adapted to engage and unseat said pilot valve member; means for normally urging said movable member away from said pilot valve member; remotely controllable means for moving said movable member to unseat said pilot valve member; indicator operating means including an element operable in response to movement of said movable member and adapted to retain said movable member in position to unseat said pilot valve member; and a member movable with said pressure operated means adapted to engage and move the element of said indicator operating means into a position to release said movable member.

4. In a valve device, the combination of a main valve having an inlet and an outlet separated by a valve seat, a valve member, means for normally urging said valve member against said valve seat, a cylinder provided with a bore of greater area than said valve member and with an aperture adjacent said valve member, a piston in said cylinder, a piston rod extending through the aperture and connecting said valve member and piston, said valve

ture and connecting said valve and piston, said valve having a passage for introducing pressure medium from the inlet side of said valve to said cylinder; a pilot valve positioned in said passage and having a valve chamber and a valve seat, a valve member in said pilot valve chamber, and means for normally urging said pilot valve member against said pilot valve seat; a movable member adapted to engage and unseat said pilot valve member, means for normally urging said movable member away from said pilot valve member; remotely controllable means for moving said movable member to unseat said pilot valve member; indicator operating means including an element operable in response to movement of said movable member and adapted to retain said movable member in position to unseat said pilot valve member; and a member adapted to engage and move the element of said indicator operating means into a position to release said movable member, said last member being positioned to be moved by said piston in said valve cylinder.

5. In combination, a valve, means for opening said valve, means for initiating operation of said valve opening means, means for indicating when said initiating means is conditioned for effecting operation of said valve opening means, means effective upon operation of said initiating means for operating said indicating means, and means movable with said valve opening means for subsequently moving said last defined means out of indicating means operating position.

6. The structure of claim 5 as set forth and defined therein, wherein said initiating means constitutes electromagnetically operated means for initiating operation of said valve opening means.

7. The structure of claim 5 as set forth and defined therein, wherein said initiating means constitutes manually operated means for initiating operation of said valve opening means.

8. The combination of a valve having an inlet, means for opening said valve including a piston and a conduit extending from the inlet to said piston, pressure responsive means for closing said valve, means including pilot valve means connected in said conduit for preventing access of fluid from said inlet to said piston and for initiating operation of said valve opening means by positive fluid pressure, means for latching said pilot valve means in valve opening operating position, means for rendering said latching means ineffective when said valve is operated towards closed position by said pressure responsive means, and means for returning said pilot valve means to its initial position when said latching means are rendered ineffective.

9. The combination of a source of fire extin-

guishing fluid under pressure, a conduit for distributing the fluid, a valve in said conduit having an inlet, means operated by the pressure from the conduit for opening said valve, means responsive to the diminution of pressure in said conduit for closing said valve, means for preventing access of fluid from said inlet to said valve opening means and for initiating the operation of said valve opening means by positive fluid pressure and being normally maintained in an ineffective condition, means for maintaining said last mentioned means in an effective condition, and means associated with said valve opening means for rendering said maintaining means ineffective upon operation of said valve by said valve closing means.

10. In combination, a valve, means operable for opening said valve, means for controlling the operation of said valve opening means, means for indicating when said controlling means is conditioned for effecting operation of said opening means to open said valve, means operable in response to the operation of said controlling means for operating said indicating means, and means movable with said valve opening means for subsequently moving said last defined means out of indicating means operating position.

11. The combination of a valve for controlling pressure fluid and comprising a housing forming main valve and pressure chambers separated by a partition adapted for preventing passage of the fluid between the chambers, an inlet to said main valve chamber and an outlet therefrom having a main valve seat, a pilot valve chamber including an outlet for the pressure fluid to said pressure chamber and having a pilot valve seat, conduit means by-passing said main valve chamber from said inlet to said pressure chamber through said pilot valve chamber; a main valve body normally held by the fluid pressure in said main valve chamber against said main valve seat; means for urging said main valve body against said main valve seat; means including means in said pressure chamber responsive to the fluid pressure for unseating said main valve body and adapted to be so connected to said main valve body through said partition as to prevent passage of the fluid through said partition; means including a pilot valve body in said pilot valve chamber; means normally urging said pilot valve body against said pilot valve seat to prevent access of the fluid from said inlet to said fluid pressure responsive means; and means for latching said pilot valve body in unseated position and being responsive to seating action of said main valve body for releasing said pilot valve body for seating by its said urging means.

HARRY C. GRANT, JR.
